E. DIXON.
TOP ROLL SADDLE.
APPLICATION FILED OCT. 20, 1917.

UNITED STATES PATENT OFFICE.

EZRA DIXON, OF BRISTOL, RHODE ISLAND.

TOP-ROLL SADDLE.

1,265,307.

Application filed October 20, 1917. Serial No. 197,709.

Patented May 7, 1918.

To all whom it may concern:

Be it known that I, EZRA DIXON, a citizen of the United States, residing at Bristol, in the county of Bristol and State of Rhode Island, have invented a new and useful Improvement in Top-Roll Saddles, of which the following is a specification.

This invention relates to certain new and useful improvements in a top roll saddle, and especially to that type employing a back saddle having only a bearing on the back roll, the middle roll being untouched by either the front or back saddles, and while the invention is particularly adapted for this type it is also capable of embodiment in back saddles bearing on either the back or middle rolls or both, such as is illustrated in my Patent No. 1087734, issued February 17, 1914.

The invention resides in the formation of a lock between the front and back saddles which will necessitate relative movement other than rotation about the axis of one saddle by the other saddle, this being accomplished in the present instance by forming a knob on the end of the front saddle to enter a socket or opening in the back saddle on relative angular movement for connecting the two saddles.

The invention further resides in the features of construction, and the arrangements and combinations of parts described in detail in the following specification and succinctly defined in the appended claims, reference being had to the accompanying drawings wherein.

Figure 1 is a side elevation of the improved saddle construction as applied to a spinning machine, the latter being in fragment.

Fig. 2 is a detailed section on line 2—2 of Fig. 1.

Fig. 3 is a fragmentary side elevation of the saddle construction showing particularly the improved lock, and

Fig. 4 is a top plan view of that portion of the saddle illustrated in Fig. 3.

Referring more in detail to the drawing, the numeral 1 indicates the front roll saddle which rides the front roll 2 and is formed with a rearwardly extending shank 3 terminating in a knob or enlargement 4, the shank being peripherally recessed, as at 5, adjacent and in advance of the knob to reduce the diameter of said shank at this particular point.

The back saddle is adapted to ride either the back roll 6 or the middle roll 7, a lateral lug 8 being formed on the shank 3 between the recess and the saddle body proper past which the back saddle is movable for assuming operative relation with either roll.

This back saddle 9 has suitable roll-straddling means 10 on its lower side and is provided with an upstanding arm 11 at its rear edge, said arm being formed with an aperture 12 and a slot 13 leading therefrom upwardly through the upper end of said arm.

In applying the back saddle to the shank of the front saddle, the latter is held in an upright position, or so that the shank will extend at right angles to the back saddle, with the peripheral recess 5 facing the inner side of the arm. The shank is then moved laterally to engage one of the opposing fingers 14 in the recess 5 and the knob 4 disposed in the aperture 12, as depicted in dotted lines in Fig. 3. The front saddle is then swung down to the full lined position and dropped from out the slot 13 into the aperture 12 in which latter the shank is freely rotatable and slidable. The front saddle is then turned to bring the saddle proper into a downwardly-facing position, the extent of rotation in this instance being substantially a quarter turn, as indicated in Fig. 2.

In its operative position, the back saddle is supported off the shank by the wall 15 formed on the opposite end of said back saddle. When it is desired to seat the saddle on the middle roll, the saddle is turned an additional quarter revolution to bring its slot 13 in alinement with the lug 8, which latter is disposed on the opposite side of the shank from the recess 5, and shifted longitudinally of the shank past the lug to the dotted line position indicated in Fig. 1.

It will therefore be noted that the saddles are angularly related in applying the back saddle to or removing the same from the shank, the swinging movement being in a plane longitudinal of the shank so that there is practically no possibility of either becoming disengaged one from the other.

Having thus described my invention, what I claim as new and desire to secure by Letters Patent is—

1. In a top roll saddle construction, a front saddle having a rearwardly extending shank formed on its extremity with an enlarged knob and a recess adjacent thereto on one side of the shank, a laterally extend-

ing lug formed on the opposite side of the shank and spaced forwardly of the recess, and a back saddle having an upwardly extending arm formed with a shank receiving aperture, the latter having an entrance slot leading through the upper end of the arm to provide spaced fingers for engaging in the recess of the shank on removing and mounting the back saddle over the knob from and to operative position on the shank.

2. In a top roll saddle construction, a front saddle having a rearwardly extending shank terminating in a knob and formed with a recess adjacent the knob, a lug provided on the shank in spaced relation to the recess and staggered relative thereto, and a back saddle having an upstanding arm bifurcated at its upper end to engage in the shank recess to permit movement of the back saddle from and to operative position on the shank.

3. In a top roll saddle, a front saddle and a back saddle, holding means on the back

saddle, and means on the front saddle engageable with said first named means when the saddles are at relatively right angles, said means being formed to effect locking of the saddles upon relative pivotal movement following said right angular disposition.

4. In a top roll saddle construction, a pair of saddles, one having a shank formed with a side recess adjacent its end and the other having an opening receiving the shank and defined by an overhanging part movable into the recess to permit the end of the shank being swung through the opening to disconnect the saddles.

In testimony whereof I have signed my name to this specification in the presence of two subscribing witnesses.

EZRA DIXON.
